Inventor:

Herman G. Papé.

UNITED STATES PATENT OFFICE.

HERMAN G. PAPE, OF NEW YORK, N. Y.

DESIGN FOR A HOUSING FOR PHONETIC INSTRUMENTS.

57,718.

Specification for Design.

Patented Apr. 26, 1921.

Application filed April 27, 1920. Serial No. 377,125. Term of patent 14 years.

To all whom it may concern:

Be it known that I, HERMAN G. PAPE, a citizen of the United States, residing at New York, in the county of New York and State of New York, have invented a new, original, and ornamental Design of a Housing for Phonetic Instruments, of which the following is a specification, reference being had to the accompanying drawing, forming part thereof, in which—

Figure 1 is a front elevation of the same. Fig. 2 is a rear elevation of the same. Fig. 3 is a side view of the outer contour line taken across that section which is located between the arrows "a" and "b" of Fig. 1, with the perforations "x" omitted. Fig. 4 is a side view of the outer contour line of Fig. 2, as taken across that section which is located between the arrows "c" and "d," showing the case or body portion of the housing only. The dotted lines "g—h" and "i—j" showing the relative heights of the elevations "1, 2, 3 and 4."

The leading features of my design reside in the circular body or casing "e," for which is provided the cap or front piece "f;" the annular elevation or embossure "4" of the body; the further elevations "3" thereof;

the high elongated elevations "1" on the front piece; the round and slightly reduced elevations "2" within the field of the latter; together with any suitably arranged set of perforations "x" located within the plain surrounded by the last named elevations.

The housing is particularly useful for all forms of microphonic transmitters, and particularly all forms of portable or hand transmitters; audiphone transmitters; miners', firemen's, or telephone operators' chest, cheek, or body transmitters; doctors' stethoscopic transmitters; pocket transmitters; vestibule flush wall transmitters, etc., in which cases the field portion "y" located within the annular elevation "4" of the body portion serves then ideally for the mounting or embedding of the microphone element or elements employed.

I claim:

The ornamental design for a housing for phonetic instruments as illustrated and described.

Signed at New York, in the county of New York and State of New York, this 26th day of April, 1920.

HERMAN G. PAPE.
